VIBRATING MOTOR

Filed Oct. 16, 1926

Inventor
John Meeker High, Jr.
By his Attorneys Darby & Darby.

UNITED STATES PATENT OFFICE.

JOHN MEEKER HIGH, JR., OF NEW YORK, N. Y.

VIBRATING MOTOR.

Application filed October 16, 1928. Serial No. 142,139.

This invention relates broadly to vibrating motors, particularly of the type employed in sound reproducing devices.

One of the objects of this invention is the provision of a new and novel construction for vibrating motors, which is relatively simple and easy to construct, and which is particularly adapted for cheap manufacture and quick assembly.

10 Another object of this invention is the provision of a simple and novel means for mounting all the parts of a vibrating motor on the permanent magnet by means of a simple clamping arrangement.

15 Another object of this invention is the provision of a single support for the pole pieces, solenoids and armature, which is adapted to be quickly clamped to the permanent magnet.

20 These and many other objects are successfully sought by means of the construction of this invention.

This invention resides substantially in the combination, construction, arrangement and 25 relative location of parts, as will appear more fully in the following description.

Referring to the drawings, in which the same reference numerals will be used in the several views to indicate the same or similar 30 parts,

Fig. 1 is a plan view of my improved vibrating motor.

Fig. 2 is an end elevational view of the motor.

35 Fig. 3 is a cross-sectional view with some parts broken away, taken on the line 3—3 of Fig. 2, looking in the direction of the arrows, showing the pole pieces, solenoids, etc.

Fig. 4 is a cross-sectional view, with some 40 parts broken away, taken on the line 4—4 of Fig. 1, looking in the direction of the arrows.

Fig. 5 is a similar cross-sectional view taken on the line 5—5 of Fig. 1.

45 Fig. 6 is a perspective view of one of the pole pieces, and

Fig. 7 is a perspective view of the armature and its mounting.

I am well aware that vibrating motors of 50 this general construction are well-known in the art, but I have provided certain principles of construction which adapt vibrating motors of this type for ease in manufacture and assembly.

55 One of the important features of the in-

vention resides in the construction employed for mounting all the parts of the instrument on a single support, which is adapted to be clamped to the permanent magnet.

In the drawings is shown the vibrating 60 motor of the differential type, comprising a V-shaped permanent magnet 1. While I have disclosed a V-shaped permanent magnet for use in my device, I am, of course, aware that other forms, such as the U-shaped 65 type, may be employed, but I have found that in actual manufacture the V-shaped type of magnet is readily adapted for manufacture in large quantities. The pole pieces 2, 2, are supported on a non-magnetic plate 70 3, having the integral portions 4, 4 formed thereon at right angles. The pole pieces are clamped to these arms or plates 4 by means of screws 5, which project through slots 4' in the plates 4, to provide an adjusting 75 movement for the pole pieces. At 6 is represented another integral member formed at right angles to the plate 3 by means of which the entire motor construction may be readily mounted to any suitable support. Another 80 projection lying in the plane of plate 3, as shown at 7, on which is mounted the hollow post 8, in alignment with a similar post 8 on the main body of the plate 3. A two-part resilient reed support 10 is provided, the 85 parts being clamped to the posts 8 by means of the screws 9, as is clearly shown in Fig. 5. Mounted between the two parts of the reed 10, is an armature 11, which is connected by means of a rod 12 to a spring arm 13, 90 which is, in turn, mounted on the plate 3 by means of an enlarged portion 14. The solenoid windings 15 encircle the armature as is clearly shown in Fig. 5, and are disposed one on each side of the armature support. A 95 non-magnetic bar or plate 17 is disposed on the opposite side of the permanent magnet from the plate 3, and the two are clamped together by means of a long bolt 18, as is shown in Fig. 4. These solenoid windings 100 are supported in place between the pole pieces by reason of the recesses formed therein by the projections 2', as shown in Fig. 6. The method of supporting these coils within these recesses by wedging them into place is clearly shown in Fig. 2. The parts 10 of the reed are formed with slots 10', so that they may be adjusted on their supporting posts to provide means for properly aligning the armature between the pole pieces.

The operation of the device is as follows. Let us suppose in Figure 1 that the right hand pole of the magnet 1 is the north pole and the left hand pole is the south pole. 5 When a varying alternating current, such as a voice current is supplied to the windings 15 the armature 11 vibrates between the pole pieces 2, 2. When the direction of the current through the winding is such as 10 to make one end of the armature a north pole the other end is a south pole. As a result the pole piece 2 on the north pole of magnet 1 attracts the south pole of the armature, while the south pole of magnet 1 at that 15 end repels it. The north pole of armature 11 is repelled by the north pole of magnet 1 and attracted by the south pole of magnet 1. When the current reverses the reverse operation occurs. As a result the armature vibrates back and forth at varying intensities 20 dependent upon the strength of the current in the windings 15, all as is well known in this art.

It will be seen from the foregoing description that I have provided a vibrating motor of relatively few parts, which are so constructed as to provide simple but accurate means for supporting the various parts in operative relation. The method of mounting 25 the pole pieces, solenoid coils, and armature is very simple, and provides for ready means of adjustment.

I am, of course, aware that many changes in the details of construction and arrangement of parts will readily occur to those skilled in the art, without departing from the principles of this invention, and I do not, therefore, desire to be limited to the exact construction disclosed by me, but 30 rather to the field of invention as defined in the appended claims.

What I seek to secure by United States Letters Patent is:

1. Motive means for sound producing devices, comprising a permanent magnet, a non-magnetic plate attached to said magnet, pole pieces supported by said plate, a solenoid magnet, and an armature, also sup-

ported on said plate, and means for clamping said plate to said permanent magnet. 50

2. Motive means for sound producing devices comprising a V-shaped permanent magnet, in combination with a non-magnetic plate attached to said magnet, pole pieces supported by said plate, having recesses in the adjacent ends, solenoid windings supported in said recesses, and an armature arranged within said windings and between said poles. 55

3. Motive means for sound producing devices comprising a V-shaped permanent magnet, in combination with a non-magnetic plate attached to said magnet, pole pieces supported by said plate having recesses in the adjacent ends, solenoid windings supported in said recesses, posts on said plate, a two-part reed on said posts, and an armature supported by said reed between said pole pieces. 60 65

4. Motive means for sound producing devices comprising a V-shaped permanent magnet, in combination with a non-magnetic plate attached to said magnet, pole pieces supported by said plate having recesses in the adjacent ends, solenoid windings supported in said recesses, posts on said plate, a two-part reed on said posts, and an armature supported by said reed between said pole pieces, said armature being surrounded by said windings. 70 75 80

5. Motive means for sound producing devices comprising a V-shaped permanent magnet, in combination with a non-magnetic plate attached to said magnet, pole pieces supported by said plate having recesses in the adjacent ends, solenoid windings supported in said recesses, an armature supported on said plate between said pole pieces, a resilient arm attached to said plate, and means for rigidly attaching said armature and arm together. 85 90

In testimony whereof I have hereunto set my hand on this 13th day of October, A. D., 1926.

JOHN MEEKER HIGH, JR.
